Attorney

UNITED STATES PATENT OFFICE

EDWIN W. KOCH, OF TREMONT, ILLINOIS

DICE BOX

Application filed January 14, 1930. Serial No. 420,727.

This invention relates to improvements in dice boxes, and has more particular reference to glass dice boxes, in which the dice are confined but always visible, and the primary object of the present invention, is to provide a simple and inexpensive dice box for the shaking of dice and handling of dice in "Bunco" and other similar dice games.

A still further object of the invention is to provide a dice box which can be manufactured at a nominal cost, and wherein the device is of such a structure as to step or rest on the table, in such a manner, as not to be knocked over, and the device comprising a receptacle embodying a transparent container in the nature of an inverted cup, closed at its top and open at its bottom, together with a base for closing the bottom of the container, the base being preferably made of rubber or other suitable material, as to rest flatly upon the table, and will not scratch or mar the finest finished table top or surfaces, together with circular piece of flannel disposed over the top surface of the rubber base within the confines of the receptacle which heavy flannel covering will reduce to a minimum, the sound of the moving dice within the container.

Other objects and advantages of the invention will become apparent during a study of the following description taken in connection with the accompanying drawings:

Figure 1 is an elevational view of my improved dice box.

Fig. 2 is a vertical cross sectional view therethrough.

Fig. 3 is a horizontal transverse sectional view therethrough.

Fig. 4 is a perspective view of the flannel disk.

With reference more in detail to the drawings, it will be seen that my improved dice box consists of a relatively thick base 5

formed of rubber or any other suitable material, and provided inwardly from its periphery with a relatively deep annular groove 6. A container 7 of transparent material, such as glass, or the like, is as shown, in the nature of an inverted cup being closed

at its top and open at its bottom, said container 7 at its bottom having the walls thereof, received within the groove 6 as shown to advantage in Fig. 2.

The base 5 within the confines of the groove 6 at its top is reduced as at 8, and disposed over the reduced portion 8 of the base, is a circular or disk-like sound deadening member 9, of an area greater than the area of the reduced portion 8, the peripheral edge of the disk 9 being turned down about the reduced portion 8 and confined between said reduced portion of the base and the adjacent portion of the lower or bottom end of the receptacle 7 as shown to advantage in Fig. 2.

The disk 9 is preferably formed from heavy flannel as is apparent, will reduce to a minimum, the sound of the moving dice within the receptacle 7, the dice being designated by the reference character 10.

In use, the device may be held in the hand and shaken to thoroughly agitate the dice 10 confined therein, after which the device may be deposited upon the table, with the base 5 resting flatly on the table, at which time the dice will come to rest or assume a stationary position.

Manifestly with a dice box of this character, the dangers of the box resting upon the table or like surface, being tilted or knocked over is practically eliminated, as well as the danger of marring the highly polished surface of the table.

Even though I have herein shown and described the preferred embodiment of my invention, it is to be understood that the same is susceptible of changes, fully comprehended by the spirit of the invention as herein described, and the scope of the appended claim.

Having thus described my invention, what I claim as new is:

A dice box comprising a receptacle of transparent material closed at its top and open at its bottom, a supporting base for said receptacle normally closing the opened bottom of the receptacle, said bottom being of substantially relatively flat disk like formation and having on the top face thereof an annular groove inwardly of the peripheral edge thereof for receiving the lower edge of

said receptacle, and a disc of relatively soft material covering the top face of said base and having its peripheral edge arranged within the groove, said disc presenting a sound deadening surface for the base.

In testimony whereof I affix my signature.

EDWIN W. KOCH.
